DESIGN FOR A MEAT TENDERIZER

Edward C. Karp and Sven Berglund, Belvidere,
Ill., assignors to Sanitary Scale Company,
Belvidere, Ill., a corporation of Illinois

Application April 29, 1948, Serial No. 146,046

Term of patent 14 years

(Cl. D55—1)

To all whom it may concern:

Be it known that we, Edward C. Karp and Sven Berglund, citizens of the United States, residing at Belvidere, in the county of Boone and State of Illinois, have invented a new, original, and ornamental Design for a Meat Tenderizer, of which the following is a specification, reference being had to the accompanying drawing, forming a part thereof.

In the drawing—

Figure 1 is a perspective view of a meat tenderizer, showing our new design.

Figure 2 is a top plan view of the meat tenderizer shown in Figure 1.

Figure 3 is a side elevation of the meat tenderizer shown in Figure 1; and

Figure 4 is a front elevation of the meat tenderizer shown in Figure 1.

We claim:

The ornamental design for a meat tenderizer, substantially as shown.

EDWARD C. KARP.
SVEN BERGLUND.
